UNITED STATES PATENT OFFICE.

JESSE A. B. SMITH, OF STAMFORD, CONNECTICUT, ASSIGNOR TO UNDERWOOD TYPE-WRITER COMPANY, OF NEW YORK, N. Y., A CORPORATION OF DELAWARE.

TYPEWRITING MACHINE.

Application filed July 25, 1918. Serial No. 246,649.

To all whom it may concern:

Be it known that I, JESSE A. B. SMITH, a citizen of the United States, residing in Stamford, in the county of Fairfield and State of Connecticut, have invented certain new and useful Improvements in Typewriting Machines, of which the following is a specification.

This invention relates to improvements adapted for use in connection with typewriting machines of the type in which a plurality of superposed webs of paper and interleaved carbon sheets are fed along a supporting frame movable in unison with the carriage of the typewriter, and around the platen thereof; the carbon sheets at their rear ends being fastened to a carriage or truck which is carried by said frame, and which is movable forwardly along the same toward the platen, together with the webs, during line-spacing operations, and movable rearwardly independently of the webs to bring the carbon sheets into co-operative relation with fresh portions of the webs.

In typewriting machines of the type above referred to, the superposed webs tend to move or creep one upon another as they are fed about the cylindrical platen of the machine, which is objectionable, especially when the webs have printed forms upon them to be filled in upon the typewriter; as the forms, because of the creeping of the webs relatively to one another, tend to get out of register; so that the typing, although properly placed upon the outer form, which directly receives the type impressions, would be in an incorrect position upon the carbon copies produced upon the inner webs.

One object of my invention is to prevent the several superposed webs from getting out of register with one another as they are fed through the machine and about the cylindrical platen thereof, this end being accomplished by providing means carried by the typewriter for fastening the overlying side edges of the several webs together. This is preferably done as they are fed toward but before they reach and pass about the platen, so that the webs cannot creep relatively to one another while they are advancing to or being fed around the platen.

According to the present invention, a frame along which the webs pass is provided with a device or mechanism located

adjacent to a side edge of the superposed webs, and by the use of this mechanism the side edges of the several webs may be secured together at intervals, the said fastening mechanism being operable to secure the webs together at points sufficiently close together to prevent relative movement of the webs as they pass around the platen.

Other features and advantages will hereinafter appear.

In the accompanying drawing,

Figure 1 is a view illustrating my invention as applied to an Underwood front-strike typewriting machine.

Figure 2 is a view showing the fastening mechanism by itself, and as projected upon a transverse vertical plane indicated by the line 2-2, Figure 1.

Figures 3 and 4 are fragmentary views illustrating certain details of the fastening device.

Figure 5 is a perspective view showing the front or advancing end of a plurality of superposed webs of paper fastened together along their side edges for a part of their length.

Figure 6 is a sectional view upon a larger scale, showing the features of the individual fasteners upon a plane indicated by the line 6-6, Figure 5.

Referring to the drawing, the reference numeral 7 designates a cylindrical platen carried by a shaft 8 rotatable in bearings provided in a suitable carriage; the platen being movable longitudinally to accomplish the spacing of the several letters and words typed, as is usual in typewriting machines.

Associated with the carriage, whereby the platen 7 is carried, is a suitable frame extending rearwardly from the carriage and disposed in a substantially horizontal position, said frame being made up of two side members spaced apart from one another a distance somewhat greater than the width of the webs of paper to be written upon by the typewriter, one of the side members of said frame being indicated as 9. These side members, two of which are employed as will be appreciated, may be secured together by transversely extending rods or braces 10, as many of such braces being employed as may be deemed necessary or desirable.

The side members 9 may be of channel form, and the reference numeral 11 designates a carbon carriage or carrier extending

transversely of the side members 9 and having rollers 12 running in the channels of said side members, said carriage serving as a support for one or more carbon-sheet-holding members 13; which members extend from one side of the carriage between the superposed webs of paper written on by the machine and serve to hold or support the rear ends of carbon sheets. The members 13 and their carbon sheets do not extend entirely across the width of the paper but terminate some distance short of it so as to leave a margin of paper on the other side below which there is no carbon paper. 15 On the side adjoining this margin is mounted the fastening means to be hereinafter described.

Three superposed webs of paper 14 are shown. These webs may pass along the 20 upper side of the frame and over a guide 15, and about the platen 7; while the carbon-sheet-supporting members 13, which may be in the form of fingers extending between each two superposed sheets, serve as abutments to which the rear ends of sheets 16 of carbon-coated paper or fabric may be secured.

Suitable means may be provided for fastening the superposed side edges of the webs 30 14 together. In the form of my invention illustrated, the fastening means is carried by the frame aforesaid, and is secured to the side member 9 opposite to the side to which is attached the carbon-sheet holding 35 members and adjacent the edge of the paper below which there is no carbon paper.

The particular form of mechanism for fastening the side edges of the webs together is a matter of secondary importance, and 40 any suitable device for accomplishing that end may be employed. The fastening means illustrated, however, comprises jaws 17, 18 movable relatively to one another by means of handles 19, 20; the former of said jaws 45 being secured to a side member 9, and the latter of which rises and falls as the handles are operated. The movable jaw 18 carries a cutter 21, see Figures 3 and 4, which cuts out a triangular tongue of material 50 from the overlying side edges of the superposed webs 14, and folds and tucks the tongue through a slit also cut in the material of the sheets by a knife 22, the knife having an opening 23 into which the end 55 of the tongue enters, and after which the tongue is drawn upwardly through the slit formed by the knife. Figure 6 is an enlarged view showing a completed fastening formed by the mechanism above referred to; 60 the reference numeral 24 indicating, upon a greatly enlarged scale, an opening produced by the triangular cutter 21, the reference numeral 25 indicating the slit produced by the knife 22, while the reference numeral 65 26 designates the tongue cut out from the

opening 24 and folded upon itself and tucked through the slit 25 to fasten the several webs together.

As the platen 7 is rotated in line-spacing operations, the webs 14 and the carbon sheets 16 are advanced simultaneously about the platen and beneath a transverse rod 27 and a knife 28, and up along a paper table 29; this forward movement continuing until the typing of a set of forms has been completed. When this movement has been completed, the platen is swung upwardly about the rod 27 as a center, thereby releasing the webs and permitting them to be grasped and drawn out into a substantially straight position. When the webs are straightened out they are held by the operator, and the carbon carriage 11 pushed rearward independently of the webs, as by means of a handle 30, thus bringing the carbon sheets 16 into relation with new portions of the webs 14. The platen 7 and the paper table 29 are then turned to the position in which they are illustrated in Figure 1, after which the portion of the webs written upon may be drawn across the knife 28 and severed from the portion thereof remaining in the machine. The webs and carbon sheets are held in proper relation to the platen 7 by means of a paper shield 31, and suitable paper feed rolls 33 will be also provided, these, however, being features common in typewriting machines, for which reason they are not illustrated in detail.

Figure 5 shows in perspective three webs secured together along a portion of their overlying side edges, the fastenings 34 being of the kind produced by the fastening mechanism illustrated and hereinbefore described, and said fastenings being located at one side only of the combined work-sheet provided by the three webs shown. These fastenings are spaced along the said side edge, and extend throughout a portion only of the entire length of the webs. The fastenings may obviously be spaced according to the desires of the operator, and the exigencies of the case; the same being spaced as closely together as may be found necessary or desirable in order to prevent the sheets from moving relatively to one another as they are fed about the platen of the machine.

Variations may be resorted to within the scope of the invention, and portions of the improvements may be used without others.

Having thus described my invention, I claim:

1. In a typewriting machine, the combination with a revoluble platen, of a letter-feeding carriage for said platen, said carriage having a rearward extension over which superposed webs are fed to the platen, a carbon-sheet-carrier reciprocable forwardly and rearwardly on said extension, holders

extending from one side of said carrier between successive webs to hold the rear ends of carbon-sheets interleaved there between, and a manually-operable fastening device having two co-operating parts and mounted on the extention at the side thereof toward which said holders extend and at the rear of the rearward position of the carriage, the location of said co-operating parts being such that the adjacent margins of the webs 10 pass therebetween and may be attached together by said device when desired, said holders being so short as not to reach said margins, whereby the attached portions of 15 said margins may pass the ends of said holders without interference therewith, and relative creeping of said webs may be prevented.

2. In a typewriting machine, the combination with a revoluble platen, of a letter-feeding carriage for said platen, said carriage having a rearward extension over which superposed webs are fed to the platen, a carbon-sheet-carrier reciprocable forwardly and rearwardly on said extension, holders 25 extending from one side of said carrier between successive webs to hold the rear ends of carbon-sheets interleaved therebetween, and a web-attaching device mounted on the extension at the side thereof toward which said holders extend and at the rear of the rearward position of the carriage, said attaching device being so located that the adjacent margins of the webs pass there- 30 through and may be attached together by said device when desired, said holders being so short as not to reach said margins, whereby the attached portions of said margins may pass the ends of said holders without interference therewith, and relative creeping of said webs may be prevented.

3. In a typewriting machine, the combination with a revoluble platen, of a letter-feed-

ing carriage for said platen, said carriage having a rearward extension over which 45 superposed webs are fed to the platen, a carbon-sheet-carrier reciprocable forwardly and rearwardly on said extension, holders extending from one side of said carrier between successive webs to hold the rear ends 50 of carbon-sheets interleaved between said webs, said holders extending only partially across said webs so as to leave marginal portions of the latter beyond the ends of said holders, and a manually-operable fastening 55 device having two co-operating parts so located that said marginal portions of the webs are fed therebetween and may be attached together at any desired points, whereby the attached parts of said marginal portions may be fed past the ends of said holders without interference, and relative creeping of said webs may be prevented.

4. A machine for typing superposed loose webs with interleaved carbons, each web 65 having a succession of forms printed thereon, the forms on each web being in register with those on the remaining webs, comprising a revoluble platen around which the webs are fed, line by line during the typing 70 operation, whereby a tendency is set up to cause the plies of the web to creep upon one another, and means to prevent such relative creeping, comprising a device provided upon the typewriting machine at the intake side 75 of the platen to act upon the edges of the loose webs as they approach the platen to fasten said webs firmly together, by an interlocking device which passes around said platen with said webs while leaving the in- 80 terleaved carbons loose.
